UNITED STATES PATENT OFFICE.

CHARLES K. KELLEY, OF LEAD, SOUTH DAKOTA.

GAGE.

1,246,752.

Specification of Letters Patent. Patented Nov. 13, 1917.

Application filed March 7, 1917. Serial No. 153,017.

To all whom it may concern:

Be it known that I, CHARLES K. KELLEY, a citizen of the United States, residing at Lead, in the county of Lawrence and State 5 of South Dakota, have invented new and useful Improvements in Gages, of which the following is a specification.

This invention relates to a gage and more particularly to that type of gage known as 10 a water gage and used upon boilers, and the like.

The primary object of the invention is the provision of a gage of this character which is automatically operable upon the breaking 15 of the gage tube to prevent the escape of fluid from the device with which the gage is connected.

Another object of the invention is the provision of a gage of this character which 20 is so constructed as to enable gage tubes of different lengths to be used in connection therewith and upon the breaking of the tube will enable the same to be quickly and easily replaced.

25 With these and other objects in view, the invention resides in the novel combination and arrangement of parts, which will be hereinafter described and particularly pointed out in the claims.

30 The preferred embodiment of the invention has been illustrated in the accompanying drawings, although no restriction is necessarily made to the precise details of construction therein shown, as changes, alterations, 35 and modifications, within the scope of the claims may be resorted to when desired.

In the drawings:

Figure 1 is a view in side elevation of a 40 gage constructed in accordance with the invention, and showing the same applied to a portion of a boiler.

Fig. 2 is an enlarged longitudinal sectional view through one of the valve casings 45 and showing the gage tube supporting one of the valves in the casing in normal or open position.

Fig. 3 is an enlarged sectional view 50 through one of the valve casings included in the gage and showing the valve on the tube holding member associated therewith in closed position.

Fig. 4 is a horizontal transverse section on the line 4—4 of Fig. 2.

55 Fig. 5 is a view similar to Fig. 4 on the line 5—5 of Fig. 2.

Like characters of reference denote corresponding parts throughout the several views in the drawings.

Referring now to the drawings in detail, 60 the letter A designates the improved gage in which a pair of valve casings 10 are connected with an end of a boiler 11 by pipes 12 having openings therein. The opening in one of said pipes is provided with a plug and the opening in the other of said pipes with a drain valve, as shown. Each valve casing has mounted to slide thereon a tube holding member 13. The said tube holding members receive therebetween and engage the gage 70 tube 14 of the usual type.

Within each valve casing 10 is a partition 15 dividing the valve casing into valve chambers 16 and 17, said partition 15 providing a seat for a valve 18, the stem 19 of 75 which is adjustably mounted in a cap 20 closing an end on the casing 10, said valves 18 controlling communication between the chambers 17 and the boiler 11.

The bottom of each valve casing 10 is 80 closed by a cap 20' having an opening therein, the wall of which is ground to form a seat 21 for a valve 22 arranged in the chamber 17 with the stem 23 of the valve passed through the opening 24 in the bottom of said 85 cap. A flange 25 on the cap 20' extends circumferentially of the opening 24 and is exteriorly threaded for connection with internally threaded collar 26 which is shouldered to form a seat for a guide plate 27 through 90 an opening in which the stem 23 is passed. The collar 26 is flanged at one end to form a stop shoulder 28.

Each collar 26 connected with each valve casing 10 extends within a tube holding 95 member 13 which is free to slide upon the collar and comprises a sleeve 29 at one end of which is an inturned flange forming a stop shoulder 30 and having adjustably mounted thereon a packing gland 31 forming 100 a water tight connection between the sleeve 29 and collar 26. The other end of the sleeve 29 is closed by a removable plate 32 detachably connected with the sleeve 29 and the valve stem 23, and said plate has 105 formed therein openings 33. The plate 32 is flanged to form a socket 34 into which extends an end on the gage tube 14, said flange having connected therewith a packing gland 35 insuring a water tight joint 110 between the plate 32 and the end of the gage tube.

Through the above described manner of connecting the tube holding members with the valve casing 10, it will be seen that the gage tube when connected with said members holds the valves 22 disengaged from the seats 21, so that when the valves 18 are in open position, fluid from the boiler 11 may pass through the pipes 12 and through the gage.

10 A ring 36 is movable longitudinally of the sleeve 29 and has formed thereon diametrically opposed arms 37, said ring being supported upon a coiled expansion spring 38 encircling the sleeve 29 and bearing on the plate 32, said spring tending to hold the packing in the socket 34 firmly engaged with an end of the gage tube 14.

Each casing 10 has adjustably mounted thereon a sleeve 39 which extends beyond the cap 25 and has adjustably mounted thereon a band 42 for contact with the arms 37 on the ring 36, said arms projecting exteriorly of the sleeve through slots 43 therein.

25 Through the provision of the sleeve 39, it will be seen that by adjusting the sleeve upon the casing 10, the tension of the spring 38 may be regulated, and that through the adjustment of the bands 42 on the sleeves 39, the extent to which the tube holding members may be moved toward the casings 10 against the influence of the springs 38 may be controlled.

When the improved gage has been applied to a boiler as shown in Fig. 1 in the drawings, it will be seen that the gage tube acts in opposition to the springs 38 to hold the valves 22 in open position, and that upon the breaking of the gage tube, the springs 38 will slide the tube holding members on the collars 26 to a position in which the valves 22 will seat on the seats 21 and prevent the escape of fluid from the boiler 11.

With the valves 22 in the above described position and it is desired to replace the gage tube, the valves 18 are operated to close communication between the chamber 17 and boiler 11, after which one of the tube holding members 18 may be moved toward the valve casing connected therewith against

the influence of a spring 38 to permit the ends of the new tube to be arranged in the sockets 34 on the tube holding members.

With the new tube in place, the sleeves 39 may be adjusted on the casings 10 to increase or decrease the tension on the springs 38 as the occasion requires, to insure a water tight joint being formed between the ends of the gage tubes and the packings in the sockets 34 when the valves 18 are again moved to open position.

From the foregoing description, taken in connection with the accompanying drawings, it is at once apparent that a water gage has been provided which is so constructed that different lengths of gage tubes may be used in connection therewith, and is operable upon the breaking of a gage tube to prevent the escape of fluid from the device with which the gage is connected.

Having thus described the invention, what is claimed as new, is:

1. A gage comprising valve casings, valves mounted to slide therein, tube holding members connected with said valves, springs engaging the tube holding members to slide the same, a gage tube connected with the tube holding members and adapted to act in opposition to said springs, rings engaging said springs, and sleeves adjustably mounted on said casings and engaging said rings.

2. A gage comprising valve casings, caps closing the outer ends of said casings, valves carried by said caps, valves mounted to slide within said casings, tube holding members mounted to slide on said casings and connected with said last-named valves, a gage tube engaged by the tube holding members and arranged therebetween, springs engaging said tube holding members to hold the same in engagement with said gage tube, sleeves adjustably mounted on said casings and having slots therein, bands adjustably mounted on said sleeves, rings encircling said tube holding members and bearing on said springs, and arms on said rings passing through the slots in said sleeves.

In testimony whereof I affix my signature.

CHARLES K. KELLEY.
